ADJUSTABLE COUPLING

Amedee Dion, Ste. Therese de Blainville, Quebec,
Canada

Application June 4, 1941, Serial No. 396,573

1 Claim. (Cl. 285—91)

The present invention pertains to a novel adjustable coupling or joint for securing two tubular members in communication and at a selected angle to one another. The device is particularly useful in connection with the discharge member or deflector of an ensilage cutter, although it is obviously useful also in other relations. In the ensilage cutter, it is particularly desirable to adjust the direction and the angle of the deflector, and such adjustment is readily obtained by means of the present invention.

One of the objects of the invention is to provide a joint or coupling of the character described that can be adjusted in a secure and simple manner, with few manipulations and without the necessity of adjusting bolts or nuts.

Accordingly, the device comprises a pair of complementary locking rings secured to the tubular members to be coupled and having mutually contacting spherical surfaces at which the adjustment is made. In addition, there is a third ring surrounding one of the members and serving as an anchor for the tightening or locking device of the coupling. The anchor ring carries spring-pressed members engaging a fixed member and also carries latches that lock with the adjusted coupling ring. The spring-pressed members provide the necessary tension in the latches and also operate as the pivotal members for the anchor ring which preferably is placed in a plane parallel to that of the adjusted coupling ring. Adjustable tension devices such as lock nuts are provided on the spring-pressed members and on the latches to regulate the tension in the latches and the tightness of the coupling.

The invention is fully disclosed by way of example in the following description and in the accompanying drawing in which:

Figure 1 is an end view of an ensilage cutter equipped according to the invention;

Figure 2 is a detail side elevation;

Figure 3 is a detail vertical section;

Figure 4 is a detail elevation showing an angular adjustment of the parts;

Figure 5 is a plan view of one of the coupling rings, and

Figure 6 is a plan view of the anchoring ring.

Reference to these views will now be made by use of like characters which are employed to designate corresponding parts throughout.

In Figure 1 is shown a power driven ensilage cutter 1 of any construction preferred in the art and mounted on wheels 2. The cut material is discharged through a spout 3 on which is mount-

ed an extension consisting of a vertical portion 4 on which is secured a laterally extending discharge portion 5 known as a deflector.

For the purpose of adjusting the direction and the angle of the portion 5, there is provided a universal coupling between the members 3 and 4, as shown more clearly in Figure 3. To the upper end of the spout 3 is fastened a ring 7 having an outer spherical surface 8. To the lower end of the member 4 is secured a ring 9 having an inner spherical surface 10 complementary to the surface 8 and fitted for adjustment thereon. The ring 7 has a downwardly facing horizontal shoulder 11 for a purpose that will presently be described.

On the upper end of the spout 3 and below the ring 7 is mounted a floating or anchor ring 12 having a pair of diametrically opposed apertures 13 and a pair of diametrically opposite slots 14, as shown in Figure 6. In the apertures 13 are mounted pins 15 having heads 16 at the upper ends and lock nuts 17 below the ring 12. The heads are urged upwardly by coil springs 18 surrounding the pins and bearing on the ring 12.

The slots 14 receive rods 19 having lock nuts 20 at the lower ends, as shown in Figures 3 and 4. The upper ends of the rods are adapted to be received in split tongues 21 extending from the upper coupling ring 9. To the upper extremity of each rod 19 is pivotally attached a locking lever 22 adapted to be swung to a vertical locking position upon the tongues 21. The spring pressed heads 17 engage the shoulder 11 or other fixed part of the spout 3 and the locking action is obtained through the downward spring pressure on the ring 12 and rods 19.

In order to alter the angle of the deflector 5, the locking levers 22 are released by lowering to the horizontal position as illustrated in dotted lines in Figure 4. The desired adjustment is made, and the anchor ring 12 is tilted to lie parallel with the upper coupling ring 9. The rods 19 are re-inserted in the tongues 21, and the levers 22 snapped into locking position. The anchor ring 12 need not be perfectly parallel to the upper coupling ring 9 and can adjust itself to a non-parallel position by the pivotal action at the heads 16 when the lock nuts 20 are readjusted. The slots 14 allow for play of the rods 19 in the non-parallel position. Also, the desired degree of tightness in the adjusted coupling is obtained by the adjustment of the lock nuts 17 and 20.

It will now be evident that the invention provides an adjustable universal coupling that may

be set rapidly by simple manipulations and without necessarily adjusting any bolts or nuts. The above mentioned adjustment of the lock nuts is merely optional for certain purposes.

Although a specific embodiment of the invention has been illustrated and described, it will be understood that various alterations in the details of construction may be made without departing from the scope of the invention as indicated by the appended claim.

What I claim is:

A universal coupling comprising a pair of coupling rings adapted for attachment respectively

to members to be coupled, said rings having mutually contacting complementary spherical surfaces, a floating anchor ring adapted to surround one of said members, spring-pressed pins 5 slidably mounted in said anchor ring and having their upper ends engaging the coupling ring on the last named member, rods extending from said anchor ring and engageable with the remaining coupling ring, levers on said rods and 10 adapted to latch on said remaining coupling ring, and lock nuts on said pins and rods for adjusting them lengthwise in said anchor ring.

AMEDEE DION.
